UNITED STATES PATENT OFFICE

2,521,464

MEANS FOR SECURING SOLES TO UPPERS OF FOOTWEAR

James Lathan, Norwich, England, assignor to
Esdelle Patents Limited, Norwich, England

Application January 30, 1947, Serial No. 725,179
In Great Britain August 14, 1940

Section 1, Public Law 690, August 8, 1946
Patent expires August 14, 1960

3 Claims. (Cl. 36—16)

1

The present invention relates to footwear in which a strip of leather or other material extends downwardly around the outer edge of the part which extends partly or wholly around the bottom portion of the upper, and in which said strip is for example, turned in and secured at its lower edge over the marginal portions of the lower surface of the insole or midsole.

According to the present invention the upper edge of the strip is turned in a direction outwardly from the upper and sewn, together with the lower marginal portion of the upper, between a fillet of leather or other suitable material and the upper surface of the part extending partly or wholly around the bottom portion of the upper, the said strip then being turned outwardly and downwardly around the fillet to permit its lower edge to be secured in position.

In cases where the upper does not extend completely around the footwear, the securing of the parts of the edge of the strip at the point to which the upper does not extend is effected by sewing it directly between the fillet and the aforesaid upper surface.

This invention may be applied to footwear provided with so called "platform soles."

In order that the invention may be the better understood, reference is made to the accompanying drawing in which:

Fig. 1 is a side view of one form of shoe embodying the present invention.

Fig. 2 is a transverse section on line A—A of Fig. 1.

Fig. 3 is a sectional view to a larger scale than that of Fig. 2 showing more clearly the attachment of the edge of the strip to the welt of the shoe.

Fig. 4 is a sectional view showing the manner in which the upper is secured to the shoe.

Fig. 5 is a transverse section of a heel-less shoe preparatory to applying the outer sole.

Fig. 6 is a similar view of the finished sole, and

Fig. 7 is a sectional view to a larger scale than that of Figs. 5 and 6 showing more clearly the connection of the various parts one to another.

Referring to the accompanying drawings, 1 indicates the upper of the shoe, 2 the insole to which a sock or lining may be applied in the usual manner. 3 indicates a strip or length of material, in the present instance a duplex fabric, the upper edge of which is turned around a fillet of suitable material, leather for example, indicated by 4. The upper is stretched on a last and the lower marginal portion is sewn, together with the upper edge of the strip 3, between the

2

upper sole and the fillet 4, as shown in Fig. 4, and the strip 3 is then turned over to enclose the fillet 4 and extends all round the sole of the shoe as shown in Fig. 1. At parts to which the upper does not extend, the upper edge portion of the strip 3 is sewn directly between the fillet 4 and the upper sole, as shown in Fig. 3. 5 indicates a piece of sponge-rubber, which constitutes a midsole, of appropriate outline and the upper surface of which is secured by a suitable adhesive to the under surface of the insole 2. The thickness of the rubber is increased at one end so as to form a heel.

The lower margin of the fabric 3 is turned inwards under the sponge rubber to which it may be secured by a suitable adhesive, and finally there is applied to the under surface of the rubber 5 an outer sole 7, secured thereto and to the fabric 3 by means of an adhesive or by any other suitable means.

10 The shoe described with reference to Figs. 5 to 7 has a flat or substantially flat sole, and the part 5 is omitted, the soles 2 and 7 are secured directly one to the other, and an inner sock or 15 lining 8 is provided, which is secured in position by a suitable adhesive. It is assumed that in this case in place of a fabric a strip of crepe rubber 3a is employed.

20 The respective soles may be formed of rubber or any other suitable material and instead of sponge rubber cork or any other suitable material may be substituted for the part 5 shown in Figs. 1 to 3. Moreover instead of being composed of fabric the strip 4 may be formed of 25 crepe rubber or any other suitable material.

I claim:

30 1. Footwear comprising an inner sole, and outer sole, an upper having an outwardly extending lower edge portion at least partly coextensive with the upper margin of said inner sole, a fillet overlying a marginal portion of said inner sole and said outwardly extending edge, a cover strip extending around and connected at its lower edge to said outer sole and extending upwardly over the top of said fillet, then downwardly around the inner edge of said fillet, then outwardly under said fillet and having its upper edge disposed between the bottom surface of said fillet and said inner sole and the lower edge 35 portion of said upper, and a row of stitches extending through and connecting said fillet, said upper edge of said strip, said inner sole, and said lower edge portion of said upper so far as the same is coextensive with said margin of said inner sole.

2. Footwear comprising an inner sole, and outer sole and intermediate sole, an upper having an outwardly extending lower edge portion at least partly coextensive with the margin of said inner sole, a fillet overlying the edge portion of said inner sole and the lower edge portion of said upper, a cover strip secured at its lower edge to and extending around said outer sole, said strip extending upwardly therefrom outside said intermediate and inner sole and outside and substantially completely around said fillet and terminating in an outwardly directed edge portion interposed between said fillet, said inner sole and the lower edge portion of said upper where it is coextensive with the margin of said inner sole and said inner sole, and a row of stitches extending through and connecting, in successive superimposed relation, said inner sole, the outer edge portion of the upper where it is coextensive with the inner sole, the outwardly directed edge portion of the cover strip and the fillet.

3. Footwear comprising an inner sole, an outer sole, a forwardly tapering, resilient body interposed between said inner sole and said outer sole to provide a heel, an upper having an outwardly lower edge at least partly coextensive with the upper margin of said inner sole, a fillet

coextensive with said margin, a cover strip secured at its lower edge to and extending around said outer sole, said strip extending upwardly therefrom outside said resilient body and said inner sole, and outside and substantially completely around said fillet and terminating in an outwardly directed edge portion interposed between said fillet, said inner sole and the lower edge portion of said upper where it is coextensive with the margin of said inner sole, and a row of stitches extending through and connecting, in successive superimposed relation, the inner sole, the outer edge portion of the upper where it is coextensive with the inner sole, the outwardly directed edge portion of the cover strip and the fillet.

JAMES LATHAN.
